OSTEOTOME

Marshal T. Seagrave, Palo Alto, Calif., assignor of
one-half to Clarence E. Butler, Oakland,
Calif.

Application October 12, 1940, Serial No. 360,907

1 Claim. (Cl. 32—61)

The invention, in general, relates to dental instruments and more particularly relates to means for facilitating the extraction of teeth.

One of the most common tasks confronting those in the practice of dentistry is that of extraction, and such work is now often referred by those skilled in the art to specialists, or exodontists. As a general rule, the extraction of any given tooth, either from the alveolar processes of the mandible or of the maxilla, does not present a particularly difficult problem to a proficient exodontist, especially where he is aided by an X-ray picture showing the location and direction taken by the roots of the tooth to be extracted. However, notwithstanding X-ray photography, it frequently occurs that extraction is impossible without a division of the alveolar processes adjacent to the tooth being worked upon. This is due to the fact that the alveolar process on the labial side of the tooth has a relatively high elasticity, the tension of which cannot be snapped or overcome by the normal force or pull, that can be exerted with the use of forceps, without recourse to violent means and ensuing trauma. In making or effecting a fracture (division) of the alveolar process adjacent to the tooth to be extracted, those skilled in the art have heretofore utilized chisels, or other like instruments independent of the conventional dental forceps, which use often results in a splintering or shattering of the bony plate, and consequently tedious labor on the part of the exodontist in removing portions of the splintered bone, as well as shock and discomfort to the patient.

A primary object of my invention is to provide a dental instrument affording the dual function of forceps and bone-dividing element so that extraction of teeth can be accomplished with ease and a minimum of time.

Another object of the present invention is to provide an osteotome of the aforementioned nature which is additionally characterized by its ease of manipulation and dependability of operation.

A still further object of the invention is to provide a dental instrument of the aforementioned character which affords a positive grip upon a tooth to be extracted and simultaneously positions the dividing element for actuation.

Another object of my present invention is to provide an instrument of the aforementioned character which affords a localized fracture (division) of the labial alveolar process rather than a splintering or shattering fracture there-

of adjacent a tooth to be extracted and thus enables extraction of a given tooth with a minimum of pain and discomfort to a patient as well as speedy extraction.

Another object of the present invention is to provide a relatively heavy duty dental instrument exemplified in a light duty structure.

A still further object of the present improvement is to provide an osteotome of the indicated nature which is relatively inexpensive and simple to manufacture.

Other objects of the invention, together with some of the advantageous features thereof, will appear from the following description of a preferred embodiment of the invention, as well as certain modifications thereof, which are illustrated in the accompanying drawings. While I have depicted certain embodiments of the invention in the drawings, it is to be understood that I am not to be limited to the precise embodiments shown, nor to the precise arrangement of the combined elements, as my invention, as defined in the appended claim, can be embodied in a plurality and variety of forms.

Referring to the drawings:

Figure 1 is a perspective view of a preferred embodiment of the invention.

Figure 2 is a side elevational view of the preferred embodiment of my invention, this view showing the instrument as applied to a tooth.

Figure 3 is a perspective view of a modified embodiment of the invention.

Figure 4 is a side elevational view of the modification illustrated in Figure 3, this view showing the instrument as applied to a tooth.

Figure 5 is a perspective view of another modification of the invention, the dotted lines showing the assumed positions of the actuating means for the dividing element.

In its preferred form, the osteotome of my invention preferably comprises a pair of forceps including a pair of opposed gripping jaws, and a bone dividing element supported adjacent one of said jaws, together with means for actuating said dividing element.

As illustrated in Figures 1 and 2 of the drawings, that portion of the osteotome of my invention which affords a gripping action upon a tooth to be extracted comprises a pair of forceps of somewhat the conventional type which includes a pair of handles 11 and 12 each having a gripping jaw 13 and 14, respectively, thereon. The handles 11 and 12 are pivotally connected together by means of a pin 16, and intersect one another adjacent the pin in the usual manner so

that the jaws are arranged in opposed relationship. It is clear that upon compression of the handles, or bringing of the same together, the jaws 13 and 14 are brought together, while movement of the handles 11 and 12 away from one another will move the jaws apart. Preferably, the outer surfaces, as well as the edges of the handles 11 and 12, are knurled to facilitate handling thereof and I also conveniently turn one of the handles, such as the handle 12, upon itself 10 slightly to provide a finger grip 17. It is to be understood that the specific type of forceps depicted in the drawings is for purposes of explanation only and that the invention does not reside in a pair of forceps, per se.

The bone-dividing element that I preferably provide in the osteotome of my invention comprises a length of wire 18 that is formed with a knife edge, or sharpened to provide a blade 19 on its outer or exposed end. Any suitable wire, such as the so-called Bowden wire, can be employed for this purpose. The length of wire 18 is preferably movably housed in a tube 20 which is nearly co-extensive in length with the wire and which serves as a guide therefor. While I have specified and illustrated a Bowden wire having a sharpened outer end as the preferred bone-dividing element, it is to be understood that a blade can be movably mounted in the same manner as the wire with the same efficacious result. In accordance with the invention, I provide relatively simple means for actuating the bone-dividing element, the actuation thereof effecting the projection and retraction of the wire 18 within predetermined limits so that the blade or knife edge 19 thereof will be injected only the requisite distance into the alveolar process effectively to divide the same without splintering or shattering the plate. To this end, I preferably provide a bell-crank, designated generally by the reference numeral 21, which conveniently is mounted on one of the handles of the forceps, such as the handle 12, for ready movement by the user when desired. As shown, the inner end of the bone-dividing element 18 is secured to a relatively small link 22 which in turn is pivotally connected, by means of a pin 23, to a link 24 of the bell-crank 21. The link 24 extends through a slot 26 formed in the handle 12 of the forceps and is pivotally mounted on the axle 27 of the bell-crank which pierces the handle 12 and spans the slot 26 therein.

The mounting arrangement of the bell-crank 21 is such that the manipulating lever 28 thereof, which can be integral with the link 24, is disposed on the outside of the handle 12 for ready access. It will be clear from an inspection of the drawings that pivotal movement of the manipulating lever 28 of the bell-crank in one direction will effect a projection of the blade 19 of the division element 18 into the alveolar process while movement of the manipulating lever 28 in the opposite direction will effect a retraction of the blade from the bone-plate. Preferably, the outer extremity of the division element 18 is slidably mounted or disposed in a recess or groove 29 formed in the inner face of the jaw 14 of the forceps, and the division element is cut to such length that when it is in its fully retracted position, the tip of the blade 19 does not extend beyond the tip of the jaw.

In Figure 2 of the drawings, I have depicted the preferred embodiment of my invention as applied to a tooth 31 to be extracted, this view showing a cross-section of the jaw-bone 32 with the labial side 33 of the alveolar process at the

left and the lingual side 34 of the alveolar process at the right; this view also showing the fibrous lining, or periosteum 36, of the alveolar processes. As indicated, the osteotome of my invention is functionally operable with the jaw that carries the bone-dividing element disposed either on the labial or lingual alveolar process and the two jaws of the forceps are gripping the tooth to be extracted. The full and dotted line showings of Figure 2 of the drawings illustrate the relative positions of the blade 19 of the division element and of the bell-crank 21 upon use thereof for dividing the bony-plate. When the bell-crank has been actuated so as to bring the manipulating lever 28 thereof into engagement with the outer face of the handle 12 of the forceps, the division element 18 will be projected so that the blade 19 thereof is inserted into the alveolar process to fracture (divide) the same, all as indicated by the full line showings of Figure 2. To retract the division element from the plate, the manipulating lever 28 is merely moved in the opposite direction, as indicated by the dotted line showing of Figure 2. It requires but an instant, and one manipulation of the bell-crank to effect the fracture (division) of the bony process, and since the gripping jaws 13 and 14 of the forceps are at the moment engaging opposite sides of the tooth being extracted, the tooth can readily be lifted from the alveolar processes immediately upon the division of the bony plate.

In Figures 3 and 4 of the drawings I have illustrated a modified embodiment of the invention which is generally similar to the preferred embodiment in that it comprises a pair of forceps of somewhat the conventional type including a pair of handles 111 and 112 having opposed jaws 114 and 113, respectively, extending therefrom; the handles being pivotally connected together in the standard manner by means of a pivot pin 116. In this modification, a bone division element 118 is associated with the forceps and consists of a length of wire, such as a so-called Bowden wire, that is sharpened at its exposed end to form a knife edge or blade 119 thereon; the wire, as in the case of the preferred embodiment being sheathed for protection thereof and for the guiding of the same in a tubing 120. Preferably, the tubing 120 is curved from adjacent the inner side of one handle to the exterior of the other handle in order that the wire 119 is effectively supported as well as to insure positive sliding movement thereof in the tubing. To this end, a slot 115 is formed in handle 111 for passing tubing 120 therethrough and I preferably form a recess or groove in the exterior side surface of handle 112 for snugly and firmly receiving the tubing. Moreover, I preferably cut tube 120 to such a length that it extends slightly beyond the tip of the jaw 113 thus affording a portion thereof for partially separating the gingiva adjacent the tooth to provide for ready access of the blade 119 of the division element into the underlying bone.

The modification of Figures 3 and 4 is provided with the same means for actuating the division element as in the case of the preferred embodiment, and includes a bell-crank 121. As shown, the inner end of division element 118 is connected through a small link 122 and a pivot pin 123 to a link 124 which extends through a slot 126 formed in the handle 112 and which is pivotally connected to the axle 127 of the bell-crank 121. The bell-crank includes a manipulating lever 128 which preferably is formed integral with the link 124 and is mounted exteriorly of

the handle 112 for the convenience of the user. In Figure 4 of the drawings, I have depicted the modified embodiment in operable position as applied to a tooth 131 to be extracted, the showing of this view illustrating the jaw bone 132 and the alveolar process with the jaws 113 and 114 gripping opposite sides of the tooth. As so disposed, the osteotome is ready for effecting the division of the bony process and this is effectively accomplished by pressing lever 128 of the bell-crank 121 towards the handle 112 thereby forcing the blade 119 into the labial alveolar process to divide the same. The dotted and full line showings of Figure 4 illustrate the positions taken by the manipulating handle in the operation.

Another modification of the present invention in an osteotome is illustrated in Figure 5 of the drawings, this modification embodying a different type of a somewhat conventional dental forceps. As shown, the forceps include a pair of pivotally connected handles 211 and 212 having opposed jaws 213 and 214 extending at substantially right angles from the handles adjacent the pivot pin 216 joining the handles together. If desired, the free extremity of handle 211 may be curved slightly, as at 217, for affording a finger grip, and the two handles are preferably knurled to enhance the gripping thereof.

In the modification depicted in Figure 5 of the drawings, I preferably provide a bone division element which is mounted on the forceps pivot pin 216 and which consists of an arm 218 having a sharpened extremity to form a knife edge

or blade 219 thereon; the arm 218 constituting one link of a bell crank that is designated generally by the reference numeral 221. Bell crank 221 includes a link 224 having an aperture therein for passing the pivot pin 216 and also includes a manipulating lever 228 that is formed integral with the link 224 which in turn is integral with the arm 218. As shown, the manipulating lever 228 of the bell crank is extended longitudinally of the forceps alongside the handle 211 thereof for convenient manipulation by the user. It will be observed from the full and dotted line showings of Figure 5 that the blade 219 of the link or arm 218 can be forced into the alveolar process or buccal-plate adjacent a tooth to be extracted by merely depressing the lever 228, the blade 219 being retracted by movement of the lever in the opposite direction.

It is to be understood that the appended claims are to be accorded a range of equivalents commensurate in scope with the advance made over the prior art.

I claim:

An osteotome comprising a pair of dental forceps including a pair of opposed jaws one of which is formed with a groove in its inner surface, a bone-dividing element slidably supported in said groove, a tube sheathing and guiding said dividing element, and means for sliding said dividing element in said tube and said groove for injection into and retraction from a dental alveolar process.

MARSHAL T. SEAGRAVE.
